UNITED STATES PATENT OFFICE.

S. G. MORRISON, OF WILLIAMSPORT, PENNSYLVANIA.

IMPROVEMENT IN LAMPS.

Specification forming part of Letters Patent No. 37,301, dated January 6, 1863.

To all whom it may concern:

Be it known that I, S. G. MORRISON, of Williamsport, in the county of Lycoming and State of Pennsylvania, have invented a new and improved lamp for burning hydrocarbon oils without the use of chimneys, securing more perfect combustion, and preventing smoke; and I do hereby declare that the following is a full and exact description thereof, reference being had to the accompanying drawings, and letters of reference marked thereon.

The nature of my invention consists in providing the lamp with a distributing wick-tube or chamber of about three times the capacity in width of the conducting wick-tube to which it is attached, for the purpose of vaporizing the oil and to obtain an increased area for the flame by the extended thin burner, thereby affording the gas its requisite amount of oxygen for perfect combustion.

To enable others skilled in the art to make and use my invention, I will proceed to describe its construction and operation.

I construct my lamp of any desired form and material, and apply thereto a conducting wick-tube, (marked A,) containing the wick *a*,

which wick extends up into the distributing-chamber to *d d* in tube B, which tube is attached to the conducting wick-tube A, and about three times as broad. On each side of conducting-wick *a* in distributing-tube B are placed short pieces of wick C C, corresponding with middle C, the upper extreme end of *a*.

d d is the flame-wick, usually a piece of old cotton cloth or muslin, which does not require trimming. When charred it is picked out and replaced by another muslin rag. The wicks C C need not be renewed at all.

What I claim as my invention, and desire to secure by Letters Patent, is—

The distributing-tube B with the composite wicks C C C and flame-wick *d d*, in connection with the conducting-wick A *a*, so as to lessen the amount of oil raised by capillary attraction to the flame, the amount of wick exposed to the oil-reservoir being about one-third of that supplying the flame, the whole constructed and operating substantially as specified.

S. G. MORRISON.
